UNITED STATES PATENT OFFICE.

LORING Q. WHITE, OF BROCKTON, MASSACHUSETTS.

LAST FOR BOOTS AND SHOES.

1,152,679.

Specification of Letters Patent.

Patented Sept. 7, 1915.

Application filed December 10, 1914. Serial No. 876,568.

To all whom it may concern:

Be it known that I, LORING Q. WHITE, a citizen of the United States, residing in Brockton, in the county of Plymouth and State of Massachusetts, have invented an Improvement in Lasts for Boots and Shoes, of which the following description, in connection with the accompanying drawings, is a specification, like characters on the drawings representing like parts.

This invention relates to a last for boots and shoes and especially boots or shoes provided with a Goodyear welt, and has for its object to provide a last having a removable toe piece, with an inexpensive, strong and efficient coupling mechanism for securing the toe piece in fixed relation to the body portion of the last, and which is capable of withstanding substantially great pressure and strain to which it is subjected in the various processes through which a welted shoe passes in the manufacture of the same.

The invention further has for its object to provide a coupling mechanism which can be applied to the last at a minimum expense and in a minimum time.

These and other features of the invention will be pointed out in the claims at the end of this specification.

Figure 1 is a side elevation with parts in section of one form or construction of last embodying this invention. Fig. 2, an inverted plan of the front portion of the last shown in Fig. 1. Fig. 3, a plan of the detachable toe portion of the last inverted. Fig. 4, an end elevation of the toe piece looking at the rear wall thereof. Fig. 5, an end elevation of the body portion looking at the front wall thereof, and Fig. 6, a section of a modified form of toe piece.

In the present instance I have shown one construction or form of last embodying the invention, and which comprises a body portion *a* composed of two parts 10, 12, which are hinged together and normally kept in their operative position by a spring 13 in a manner well understood.

The fore part 12 of the body portion has detachably secured to it, by a coupling mechanism as will be described, a toe piece *b*. The coupling mechanism herein shown comprises two members *c*, *d*, which are located in slots or cavities 14, 15, in the bottoms of the toe piece *b* and the body portion *a*, and are secured to said parts by screws 16, 17, or otherwise.

A last employed in a Goodyear welt shoe usually has to remain in the shoe from five to eight days, and is subjected to severe pressure and strain in some of the processes through which the shoe passes, such for instance as the sole laying, and leveling processes, and while the shoe is passing through these processes, the lasts in them are subjected to a pressure of several thousand pounds. To enable a coupling mechanism to withstand this severe pressure, the members *c*, *d*, are preferably made as herein shown.

The member *c* consists of a substantially thick metal plate or bar, see Figs. 1, 3 and 4, from which projects a tongue 21 of substantial thickness and located between the upper and lower surfaces of the bar or plate *c*, and is provided with a slot 22 extended from its front edge, for a purpose as will be described.

The member *d* consists of a substantially thick rear plate or bar having forwardly projecting top and bottom arms 24, 25, which are separated from each other a distance approximately equal to the thickness of the tongue 21, so that the latter can be inserted between the arms 24, 25, and engaged therewith with sufficient friction to enable the toe piece to be secured to the body portion against removal except with considerable effort.

Provision is made for clamping the arms 24, 25, upon the tongue 21 after the latter has been inserted between said arms, and for this purpose a screw or bolt 30, passes freely through an opening in the lower arm 25 and engages a threaded opening in the upper arm, the said screw passing through the slot 22 in the tongue when the latter is in its operative position between the arms 24, 25.

By backing off the screw 30 slightly, the clamping arms spring apart or open up sufficiently to permit the tongue 21 to be readily inserted between them by movement of the toe piece *b* toward the body portion *a*, and when the toe piece has been brought into its operative position shown in Figs. 1 and 2, the screw 30 is set up so as to draw the arms 24, 25, toward each other, and thereby clamp the tongue between them with such force as to firmly attach the toe piece to the body portion and render it immovable until the screw 30 is released. In order to strengthen the last where the toe piece joins the body portion of the last, the clamping arms 24, 25, project beyond the front face or

end of the body portion *a*, and the tongue 21 projects beyond the rear face of the toe piece *b*, so that when the toe piece is attached to the body portion, the projecting parts overlap, and the joint between said toe piece and body portion is reinforced by metal of sufficient thickness to withstand the heavy pressure of the sole laying, leveling and other machines employed in the manufacture of boots and shoes and especially the Goodyear welt boots and shoes. By reference to Fig. 1, it will be seen that the joint between the toe piece and body portion of the last is bridged by the thickness of the clamping arms 24, 25, and the tongue 21, whose total thickness is equal or substantially equal to the thickness of the plates or bars *c*, *d*, and when the set screw 30 is set up the arms 24, 25, and tongue 21 become practically one piece, and consequently the toe piece *b* is attached to the body portion *a* by a metal plate or bar of sufficient thickness to withstand the severe pressure referred to.

The cavities 14, 15, in the bottom of the body portion and toe piece are of sufficient depth to receive the coupling members and leave the bottom of the last smooth, when the parts are in their operative relation shown in Fig. 1. The toe piece *b*, being detachable, can be replaced by other toe pieces of different shapes or designs, and for this purpose each toe piece is provided with the tongue member *c*. In Fig. 1, I have shown the last as provided with a toe piece of one design or shape, and in Fig. 6 a toe piece of a different design or shape, which can be quickly and easily substituted for the toe piece shown in Fig. 1.

In the present instance the member *d* is shown as attached to the body portion of the last and the member *c* to the toe piece, but it is not desired to limit the invention in this respect as said members may be reversed.

It will be observed that the member attached to the body portion overlaps the toe piece, and the member attached to the toe piece overlaps the body portion, when the toe piece is in its operative position with relation to the body portion, and that said overlapping pieces are secured together in fixed relation, which makes a strong rigid reinforcement for the last at the joint between the toe piece and body portion.

The last may be provided at the joint between the toe piece and body portion with a layer of leather 43 or other suitable yielding material which is suitably attached to one of said parts. Furthermore the body portion *a* may be of any suitable usual or desired construction.

Claims.

1. A last for boots and shoes comprising a body portion and a toe piece separable therefrom, and means for detachably cou-

pling said parts together in such manner as to permit the toe piece to be moved bodily in the direction of the length of the last, and comprising a member secured to each of said parts and extended beyond the same substantially parallel with the bottom thereof to overlap the other of said parts, and means for detachably securing the overlapping portions of said members in fixed relation to each other. 75

2. A last for boots and shoes comprising a body portion and a toe piece separable therefrom, and means for detachably coupling said parts together in such manner as to permit the toe piece to be moved bodily in the direction of the length of the last, and comprising a member secured to each of said parts and extended beyond the same substantially parallel with the bottom thereof to overlap the other of said parts, and means to detachably secure said overlapping parts in fixed relation. 80

3. A last for boots and shoes comprising a body portion provided with a cavity in its bottom surface, a toe piece separable from said body portion and provided in its bottom surface with a cavity which registers with the cavity in the body portion, and devices located in said cavities for detachably coupling the said toe piece to the body portion, the device on each part projecting into the cavity in the other part, to permit the toe piece to be moved bodily in the direction of the length of the last. 95

4. A last for boots and shoes comprising a body portion and a toe piece separable therefrom, and means for detachably coupling said parts together in such manner as to permit the toe piece to be moved bodily in the direction of the length of the last 100 and comprising a coupling member secured to the bottom of one of said parts and provided with arms extended beyond said part and spaced apart at their outer ends and substantially parallel with the bottom of said part, a coupling member secured to the bottom of the other of said parts and provided with a tongue which extends beyond the end of said other part and between said arms when the toe piece is moved bodily 105 toward the body portion to couple the toe piece to the said body portion, and means to secure said arms and tongue in fixed relation. 110

5. A last for boots and shoes comprising a body portion and a toe piece separable therefrom, a coupling member secured to the bottom of one of said parts and provided with arms spaced apart at their outer ends and substantially parallel with the bottom of said part, a coupling member secured to the bottom of the other of said parts and provided with a tongue which extends between said arms when the toe piece is coupled to the body portion, said tongue hav- 115 120 125 130

ing a slot extended from its front edge, and a screw engaging said arms and passing through the said slot to secure said arms and tongue in fixed relation, said screw being accessible from the bottom of the last.

6. A last for boots and shoes comprising a body portion and a toe piece separable therefrom, a coupling member attached to the bottom of said body portion and projecting beyond the front end thereof, and a coöoperating coupling member attached to the bottom of said toe piece and extended be-

yond the rear end thereof, and means accessible from the bottom of the last for securing said projecting portions in fixed relation. 15

In testimony whereof, I have signed my name to this specification in the presence of two subscribing witnesses.
